[57] CLAIM

The ornamental design for a clock face or similar article, substantially as shown.

DESCRIPTION

FIG. 1 is a front elevational view of a clock face or similar article showing my new design; and FIG. 2 is a typical side elevational view of the clock face of FIG. 1.

The rear, not shown, is flat, plain and unornamented. The broken line showing of clock hands are environmental only and form no part of the claimed design.
